UNITED STATES PATENT OFFICE.

JOHN ASHLAND WHERRY, OF NEW ORLEANS, LOUISIANA.

COLLATING DEVICE FOR TYPEWRITERS.

1,351,081.

Specification of Letters Patent. Patented Aug. 31, 1920.

Application filed October 15, 1918. Serial No. 258,146.

To all whom it may concern:

Be it known that I, JOHN A. WHERRY, a citizen of the United States, residing at New Orleans, in the parish of Orleans, in 5 the State of Louisiana, have invented certain new and useful Improvements in Collating Devices for Typewriters; and I do hereby declare the following to be a full, clear, and exact description of the invention, 10 such as will enable others skilled in the art to which it appertains to make and use the same.

This invention relates to a collating device for typewriters.

15 The primary object of the invention is to provide means whereby the several sheets of work may be assembled and conducted to the printing position of the platen without disarrangement and without being provided with any alining devices.

A further object of the invention resides in so constructing the device that it may be attached to typewriters of various forms now in commercial use, with the minimum 20 alteration of the typewriter constructions.

With these and other objects in view, such as will appear as the description progresses, the invention comprises the combination and arrangement of parts as set forth in and 25 falling within the scope of the appended claims.

In the drawings:

Figure 1 is a perspective view of the invention showing the same attached to a 30 typewriter, only a portion of the latter, however, being shown;

Fig. 2 is a front elevation of the device and so much of the typewriter as is shown in Fig. 1;

40 Fig. 3 is a side elevation showing the device in the printing position;

Fig. 4 is a vertical sectional view with the parts occupying the positions they occupy in Fig. 3;

45 Fig. 5 is an enlarged sectional view showing the manner in which the platen is clamped to the platen turning mechanism;

Fig. 6 is a perspective view of one clutch member which is carried by the platen;

50 Fig. 7 is a longitudinal sectional view of the sheet clamping means;

Fig. 8 is an enlarged sectional view of the sheet clamping means;

55 Fig. 9 is a sectional view showing the manner in which the sheet clamping means is locked;

Fig. 10 is a perspective view of the sheet clamping means;

Fig. 11 is a rear elevation of the entire device;

60

Fig. 12 is a detail of the sheet shelf supporting device;

Fig. 13 is a fragmental detail section on the line 13—13 of Fig. 11, and

Figs. 14 and 15 are fragmental views of 65 modified forms of sheet guiding devices.

In the drawing I have illustrated a portion of a typewriter which includes a frame 1, the feed roller rod 2 and the shift rod 3.

The frame of the collating device comprises side bars 4 which are secured together at their ends by transverse rod 5. The collating board 6 is secured to this frame at one end by screws 7 and at the other end by brackets 8, which extend transversely of 75 the board and beneath the same, the ends of the brackets being depressed, as shown at 9, so as to afford a free passage for the slides of the sheet clamping means, as will appear. This collating board and frame 80 are pivotally mounted on links 10, which are pivoted at 11 to the side bars 4 of the frame and at 12 to brackets 13. These brackets 13 are secured at 14 to the typewriter frame 1 and are braced by a transverse rod 15, which 85 extends beneath the collating board. The free end of each of the links 10 projects beyond the pivot point 12 and is adapted to engage a pin 16 extending from the adjacent side bar 4, so as to maintain the collating board in substantially a horizontal position. At the edges of the collating board, but slightly spaced therefrom, are scales 17 by means of which the positions of the several sheets to be collated is determined, as 95 will be readily understood.

It will be seen that the several sheets of paper with the carbons interposed between them, may be placed upon the surface of the collating board 6, with the edges abutting 100 the scale 17 and thus properly arranged to subsequently be fed to the platen in printing position.

In order that these sheets may be held in the proper relation to each other on the collating board, I have provided a sheet clamping device which includes a pair of slides 18. These slides are mounted and operate upon the side edges 19 of the collating board, as clearly shown in Fig. 1. A bar 20 extends 110 between and is secured to these slides 18, the intermediate portion of the bar being

provided with a depression 21 for a purpose which will later be described. A plate 22 is secured to one of the slides 18 by suitable fasteners 23, and this plate is provided 5 with an upwardly extending leaf spring 24. A hinge member 25 is mounted on the plate 22 and one of the leaves of the hinge is provided with a projection 26, against which the spring 24 bears to normally hold the 10 hinge in such position that the upper clamping bar 27 which is secured to the hinge at 28 is held parallel to the lower clamping bar 20. On the end of the upper bar 27, opposite to the hinge end, a spring pressed 15 tongue 29 is mounted, the tongue being arranged to coöperate with a socket 30 to form a latch to hold the clamping bar 27 in position. A sheet engaging bar 31 is located between the clamping bars 20 and 27 20 and is yieldingly mounted on the upper bar 27 by means of guide screws 32 and coil springs 33. This sheet engaging bar 31 is formed to fit in the depression 21 in the lower bar 20 and is provided with a bill 34 25 which overhangs the beveled edge 35 of the lower bar. The sheets of work pass over the lower bar 20 and are clamped against the same by the resilient pressure through the sheet engaging bar 31, so that all possibility of relative movement of the sheets 30 which are being collated is obviated. In order to prevent the upper portions of the sheets from falling away from the collating board 6 when the latter is swung to its 35 vertical position, a pair of resilient fingers 36 is secured to the upper bar 27 and extends over the collating board, as illustrated clearly in Fig. 1. A bar 36' extends from one slide 18 to the other and is located beneath the fingers 36. This bar 36' assists in maintaining the sheets of work in position since the sheets are inserted beneath it.

Located beneath the collating board 6 and mounted in the side bars 4 of the frame, are 40 rollers 37 and 37', around which endless belts 38 pass. These belts are secured to clamps 39 on the slides 18 and have counter weights 40 interposed therein. These counter weights 40 operate on guides 41, which 45 are mounted on the inner sides of the side bars 4 of the frame. Thus when the sheet clamp is moved in either direction the weights will be likewise moved.

The side bars 4 of the frame are provided 50 at the ends opposite to that between which the roller 37 is mounted with sockets 41 in which spindles 42 projecting from the ends of the platen are supported. The platen is thus supported by the side bars 4. These 55 spindles 42 are mounted within yokes 43 which extend into chambers 44 in the ends of the platen and are secured in place by plates 45. These yokes are provided with slots 46 through which slide pins 47 project, 60 the pins being extended through the spin-

dles 42 to limit the sliding movement of the spindles longitudinally within the yokes 43. The spindles are normally pressed outwardly by coil springs 48 and are provided on their ends with abutment nuts 49. The 70 pins 47 in the slots 46 limit the movement of the spindles. The ends of the spindles 42 are provided with clutch members 50 which coöperate with complementary clutch members 51. These clutch members 51 are 75 mounted on the trunnions 52 of the platen rotating mechanism, which mechanism includes the usual hand knobs 53 and also the ratchet mechanism 54. These complementary clutch members 51 are attached to the platen 80 rotating mechanism of a present commercial typewriter, with very slight modification of the mechanism, as will be obvious from an observation of Fig. 5 of the drawing. The springs 48 maintain the clutch members 85 50 and 51 in engagement with each other when the plate is in its printing position, but the springs 48 are held under compression and the clutch members 50 are retracted during the swinging of the platen, either 90 to or from its printing position, by controlling levers 55, which are mounted on the side bars 4, and the ends 56 of which project into grooves 57 in the spindles 42, as will be seen in Figs. 1 and 5 of the drawing. 95

With the collating board mounted pivotally on the brackets 13 which are supported on the frame 1 on the typewriting machine, it will be seen that the board may be swung either into substantially horizontal position 100 or substantially vertical position, and when the board is moved from its horizontal position, in which position the sheets are placed upon the board, to its vertical position the platen is swung into its printing 105 position and the coöoperating clutch members 50 and 51 are operated to engage so that the platen rotating mechanism may be effective to engage the platen. The ends of the side bars 4 at this time engage in notches 57' 110 which are formed in the rod 2. The engagement of the bars 4 in these notches prevents the frame from having any lateral movement when the frame is disposed vertically. 115

Secured to the carriage frame of the typewriter are lugs 58, to which links 59 are pivoted at 60. These links are pivoted at their opposite ends at 61 to the ends of a rod 62 and when the collating board is 120 swung from its horizontal to its vertical position, the links assume a position such as illustrated in Figs. 3 and 4 of the drawing and support the lower end of the board.

Threaded bolts 59' which are secured at 125 60' to the side bars 4 of the frame, support at their lower ends a rod 61', which rod may be adjusted vertically by means of nuts 62 on the bolts. This rod 61' is secured to and supports a sheet shelf and guide 63, 130

which is curved to conform to the curvature of the platen and which is extended and has attached thereto at 64 links 65. These links 65 are pivoted at the ends opposite to the 6 attaching means 64 at 66 to the side bars 4 of the collating frame. Openings are formed in the links 65 and extending through these openings are locking cams 68, which are provided with operating handles 10 69 and which slide in slots 67 in the links 65 during the movement of the sheet shelf from one position to another. When the cams 68 are turned so that the long diameters thereof extend at right angles to the 15 short diameters of the slots 67, the sheet support will be locked in position. Springs 71 which are attached at 72 to the side bars 4, and at 64 to the links 65, tend to maintain the sheet support in proper position 20 with relation to the platen, so that the guide rollers 73, which are mounted on the outside surface of the support and extend through openings 74 in the same, will be held in contact with the platen, and consequently properly guide the paper during its 25 feeding to printing position.

In Fig. 14 a modified form of this portion of the device is shown. In this form the bolts 59" which correspond to the bolts 59' in the previously described form, are attached to the rod 61' and are rigidly secured to the side bars 4. The rod 61' extends along the outer surface of the guide 63 and through keepers 63" which permit the guide 30 63 to move relatively to the rod 61' during the movement of the sheet shelf.

In the third form disclosed in Fig. 15 the bolts 59''' are pivoted to the side bars of the frame and are attached to the rod 61'. The rod in this case carries the rollers 73'. Therefore, when this form is used the rollers 73 of the first described form will be dispensed with.

Of course, it will be understood that after 45 the sheets are clamped in place on the collating board, they will be fed to the printing position by feeding the sheets between the sheet support 63 and the platen from the front to the rear of the latter. As the printing is subsequently done the sheets will be fed in the reverse direction, as will be obvious.

While the operation of the device is thought to be obvious from the preceding 55 description, a brief résumé is here given. The collating board 6 is in its horizontal position when the work is applied thereto. The sheets which are to be collated are placed upon the board 6, being located under 60 the bar 36' and over the lower clamping member 20, the upper member 27 having been swung into the position shown in Fig. 10, that is to say, away from the member 20. The sheets are properly assembled in 65 this position by means of the scales 17, and

the upper clamping member 27 swung into position to hold the sheets in place. The collating board is then swung into its vertical position, at which time the sheets of work will be supported by the bar 36' and 70 the fingers 36. The clutch members 50 and 51 will move into alignment with each other and when the controlling levers are operated to release them, they will automatically be engaged by the springs 48. The platen will 75 at this time be in printing position, and the frame will be held against lateral movement by the engagement of the side bars 4 in the notches 57'. With the frame in its vertical position the sheets of work are fed between 80 the platen and guide 63 until the top line to be printed is in proper position. Thereafter the sheets will be moved in the reverse direction in the usual manner.

What I claim is:

1. The combination with a platen which is bodily movable to and from operative position, of a collating board connected at one of its ends to the platen and movable with it to assume substantially vertical and 90 horizontal positions, said collating board being pivotally supported intermediate its ends and means for actuating the platen when in operative position, said means being disengageable from the platen to permit 95 the latter to be swung forwardly and upwardly to its inoperative position with the collating board face upward.

2. The combination with a rotary platen, of means for operating the same, said platen 100 being bodily movable away from said means, a collating board connected at one of its ends to the platen and movable with it to assume substantially vertical and horizontal positions, said collating board being pivotally supported intermediate its ends and 105 means for actuating the platen when in operative position, said means being disengageable from the platen to permit the latter to be swung forwardly and upwardly to its inoperative position with the collating board face upward.

3. The combination with a rotary platen, of a collating board affixed thereto, the platen and board being bodily movable in 115 unison, said collating board being pivotally supported intermediate its ends and means for actuating the platen when in operative position, said means being disengageable from the platen to permit the latter to be 120 swung forwardly and upwardly to its inoperative position with the collating board face upward.

4. The combination with a rotary platen, of a collating board affixed thereto, said 125 platen and board being bodily movable about a common pivot to assume substantially horizontal and vertical positions and means for actuating the platen when in operative position, said means being diseng- 130

- gageable from the platen to permit the latter to be swung forwardly and upwardly to its inoperative position with the collating board face upward.
5. The combination with a rotary platen of a collating board affixed thereto, platen operating means, the platen being bodily movable to and from the operating means, and collating board being movable to substantially horizontal and vertical positions, said collating board being pivotally supported intermediate its ends and means for actuating the platen when in operative position, said means being disengageable from the platen to permit the latter to be swung forwardly and upwardly to its inoperative position with the collating board face upward.
10. The combination with a rotary platen which is movable to and away from printing position and has a clutch member thereon, of a stationary clutch member arranged to engage the first clutch member when the platen is in printing position, and a collating board connected at one of its ends to the platen and movable with it to assume substantially vertical and horizontal positions.
15. The combination with a typewriter frame, of a rotatable platen, operating means for the platen including clutch members associated with the frame, clutch members on the platen arranged to engage the clutch members on the frame, means for supporting the platen whereby it may be swung away from the operating means, and a collating board associated with the platen.
20. The combination with a typewriter frame, of a collating board pivoted thereon, said board having a sheet clamping device slidably mounted thereon, counterweights associated with said device, a platen mounted on the board, and a sheet guiding device mounted on the collating board frame, whereby the work sheets may be inserted from the front down over the printing position on the typewriter and guided around the platen to the rear of the same.
25. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
30. The combination with a typewriter frame, a collating board pivoted between its ends on said frame, a rotatable platen carried by one end of the board, clutch members on said platen, complementary clutch members on the frame, and means for operating the platen when the clutch members are engaged.
35. The combination with a typewriter frame, of a collating board pivoted between its ends on said frame, means for supporting the board in substantially a horizontal position, a revolvable platen carried by one end of the board, clutch members on said platen, complementary clutch members on the frame, and means for operating the platen when the clutch members are engaged.
40. The combination with a typewriter frame, of a pair of brackets mounted thereon, links pivoted to the brackets, a collating frame pivoted between its ends to the free ends of the links, a platen carried by one end of the collating frame, and a platen operating mechanism on the typewriter arranged to receive the platen.
45. The combination with a typewriter frame, a collating board pivoted between its ends on said frame, a rotatable platen carried by one end of the board, clutch members on said platen, complementary clutch members on the frame, and means for operating the platen when the clutch members are engaged.
50. The combination with a typewriter frame, of a pair of brackets mounted thereon, links pivoted to the brackets, a collating frame pivoted between its ends to the free ends of the links, a platen carried by one end of the collating frame, and a platen operating mechanism on the typewriter arranged to receive the platen.
55. The combination with a typewriter frame, of a pair of brackets mounted thereon, links pivoted to the brackets, a collating frame pivoted between its ends to the free ends of the links, a platen carried by one end of the collating frame, and a platen operating mechanism on the typewriter arranged to receive the platen.
60. The combination with a typewriter frame, of a pair of brackets mounted thereon, links pivoted to the brackets, a collating frame pivoted between its ends to the free ends of the links, a platen carried by one end of the collating frame, and a platen operating mechanism on the typewriter arranged to receive the platen.
65. The combination with a typewriter frame, of a pair of brackets mounted thereon, links pivoted to the brackets, a collating frame pivoted between its ends to the free ends of the links, a platen carried by one end of the collating frame, and a platen operating mechanism on the typewriter arranged to receive the platen.
70. The combination with a typewriter frame, of a collating frame pivotally mounted thereon, a platen mounted on the collating frame, a sheet guide extending around the platen, there being an open space between the platen and the guide at the front of the machine, whereby the sheets may be inserted, means on the frame for moving the guide toward the platen to guide the work sheet in position, and means on the frame for moving the guide from the platen.
75. The combination with a typewriter frame, of a pair of brackets mounted thereon, a collating frame, links pivoted to the brackets and to the latter frame between the ends thereof, and links pivoted to the former frame and to the collating frame adjacent to the end thereof.
80. The combination with a typewriter frame, of a collating board pivoted thereon, said board having a sheet clamping device slidably mounted thereon, counterweights associated with said device, a platen mounted on the board, and a sheet guiding device mounted on the collating board frame, whereby the work sheets may be inserted from the front down over the printing position on the typewriter and guided around the platen to the rear of the same.
85. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
90. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
95. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
100. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
105. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
110. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
115. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
120. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
125. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.
130. The combination with a typewriter frame, of a pair of brackets and a pair of lugs mounted thereon, links pivoted to the lugs, links pivoted to the brackets, a collating frame pivoted between its ends to the free ends of the links, a platen carried by one end of the collating frame, and a platen operating mechanism on the typewriter arranged to receive the platen.

down over the printing position on the platen.

18. In a typewriter including a rotary platen and a collating board adapted to swing into vertical and horizontal positions, a sheet guiding device extending around the platen, means for swinging the guiding

device toward the platen when the collating board moves to its vertical position and away from the platen when the collating board moves to its horizontal position.

In testimony whereof I affix my signature.

JOHN ASHLAND WHERRY.
